UNITED STATES PATENT OFFICE.

ADMIRAL D. YORK, OF ENSLEY, ALABAMA.

CAN-OPENER.

SPECIFICATION forming part of Letters Patent No. 766,209, dated August 2, 1904.

Application filed March 23, 1904. Serial No. 199,608. (No model.)

To all whom it may concern:

Be it known that I, ADMIRAL D. YORK, a citizen of the United States, residing at Ensley, in the county of Jefferson and State of Alabama, 5 have invented certain new and useful Improvements in Can-Openers, of which the following is a specification.

My invention relates to can-opening devices; and the main and essential feature there- 10 of rests in the provision of an article of this class which embodies an extreme simplicity of structure, so that it can be made in quantities at a minimum cost.

Because of the extreme simplicity and cheap- 15 ness as regards the cost of manufacture of the opener it can be readily attached to cans or like receptacles which must needs be opened by a device of this type, and this is an advan- tageous feature of my invention.

For a full description of the invention and the merits thereof and also to acquire a knowl- 20 edge of the details of construction of the means for effecting the result reference is to be had to the following description and ac- 25 companying drawings.

While the essential and characteristic fea- 30 tures of the invention are susceptible of modi- fication, still the preferred embodiment of the invention is illustrated in the accompanying drawings, in which—

Figure 1 is a perspective view showing the manner of use of the device when in opera- 35 tion. Fig. 2 is a plan view of my can-opener. Fig. 3 is a side elevation.

Corresponding and like parts are referred to in the following description and indicated in all the views of the drawings by the same reference characters.

In the preferred structure of the opener the 40 same is made from a single length of material, such as wire, strip metal, or the like.

The essential parts of the device consist of the shank 1, the cutting-blade 2, formed at one end of the shank 1, and a handle member

45 3, adjacent the shank aforesaid. The drawings illustrate an opener formed from a single length of steel wire, preferably, same be- 50 ing of a suitable gage to lend the necessary strength and rigidity to the opener. The shank 1 in order to provide a cutting-blade has

the end portion thereof sharpened for this pur- 55 pose, and since the shank is made from steel the edge of the cutting-blade will be retained very readily. The shank 1 is bent to form a par- alleling arm or handle member 3, which, to- 60 gether with the shank, comprises the handle by which the device is operated. The mem- ber 3 of course constitutes a continuation or integral part of the shank and may be readily bent in the manner shown and above described. 65 The end portion of the handle member 3, which is virtually one end portion of the shank 1, is projected laterally and trans- versely across the shank-body 1 adjacent the cutting-blade 2 thereon. The transversely- 70 bent portion constitutes a fulcrum member 4, which being disposed below the shank affords a means whereby purchase may be had in op- erating the can-opener for cutting purposes. The end portion of the shank which forms 75 the fulcrum member 4 is preferably flattened, as shown most clearly in Fig. 3, to enlarge same for obvious reasons.

In operating the can-opener the point of the cutting-blade 2 is first introduced within or 75 passed through the part which it is designed to cut. Then by a continuous up-and-down movement of the handle of the opener the same will cut very readily in a straight or cir- 80 cular line, dependent upon the desire of the operator and as found necessary.

From the foregoing it will be noted that the 85 opener comprises separate members in the provision of the shank 1 and the handle mem- ber 3 and that the handle member extending across the shank forms the convenient ful- crum which has been hereinbefore described.

Since my device can be made from a single length of material, such as set forth herein- before, it will be readily seen that the cost 90 thereof is reduced to a minimum and that the can-openers may be easily secured to the can- bodies and sold therewith without appreci- ably increasing the cost of the receptacle.

Having thus described the invention, what 95 is claimed as new is—

1. A can-opener comprising a shank pro- 100 vided with a cutting-blade, a handle member spaced from the shank, and a fulcrum mem- ber projected from the handle member afore-

said and disposed transversely across the shank at a point adjacent the cutting-blade aforesaid.

2. A can-opener comprising separate members, one of said members being provided with 5 a cutting-blade, the other of said members being extended transversely across the member provided with the cutting-blade to form a fulcrum therefor.

3. A can-opener comprising a shank or 10 handle portion provided at one end with a cutting-blade and having the other end portion extended and projected transversely across the said shank adjacent the cutting-blade to form a fulcrum member.

15 4. A can-opener consisting of a single

length of material comprising a shank having an end portion sharpened to form a cutting-blade, said shank being bent to form an approximately parallel handle member, an end portion of the handle member being projected 20 transversely across the body of the shank adjacent the cutting-blade thereof to form a fulcrum member.

In testimony whereof I affix my signature in presence of two witnesses.
